PISTON FOR INTERNAL-COMBUSTION ENGINES

Application filed May 2, 1929, Serial No. 359,947, and in France May 19, 1928.

Pistons of aluminium, which are employed to an increasing degree for automobile engines on account of their lightness, are disadvantageous due to the fact that they have a coefficient of expansion which is about double that of cast iron, and it is necessary in order to prevent them from gripping in the cylinders, to allow a certain play, and this causes at slow speed, due to the low temperature corresponding to this speed, a disagreeable pounding noise, since the play allowed for the full speed is too large for the slow speed.

Attempts have been made to give a smaller play to the pistons by acting against their expansion by means of steel cross members, but this arrangement has the disadvantage of limiting the expansion to the points of junction of these cross members, and these, under the traction caused by the expansion, may become separated from the aluminium shell in which they are imbedded.

On the other hand, the said cross members have no useful action upon the bosses in which the end of the piston rod axle is mounted, and there is produced, due to the expansion of said bosses, a certain play which may be a source of noise.

The present invention has for its object to obviate these drawbacks by allowing the expansion to take place freely. For this purpose, the cross members are imbedded in the piston only at one end, if at all, and the other end, or in some cases both ends, are simply in contact with the internal wall of the peripheral part of the piston. It follows that the said peripheral wall may expand freely in the circumferential direction, and no gripping is to be feared, since this wall is split and can recede in order to rest upon the free edge of the cross member, which latter only slightly expands, so that the withdrawal of the piston wall is limited, and there is no danger of exceeding the elastic limit which might put it out of shape.

The cross members are provided at the middle with flanges which are inserted into bosses on the wrist pin, and since their expansion is about the same as that of the wrist pin, there will be practically no play at this point.

The accompanying drawing shows by way of example various embodiments of the invention.

Fig. 1 shows a piston in vertical section passing through the axis of the piston rod 55 end.

Fig. 2 is an external elevational view.

Fig. 3 is a section on the line III—III of Fig. 1.

Fig. 4 is a sectional view on the line IV—IV 60 of Fig. 2.

Fig. 5 shows a modification of the piston, in section on the axis of the bosses.

Figs. 6 and 7 shows another modification in elevational view and horizontal section. 65

In the upper part of the piston 1 (Figs. 1 and 4) are formed the grooves 2 in which the packing rings are disposed as usual. The upper part 1 is connected to the lower part 3 forming a sliding surface, by means of a support 4 carrying the bosses 5 and 6 in which is disposed the axle of the piston rod end. 70

The lower part 3 is separated from the upper part by an annular slot 7 and it is also subdivided by vertical slots 8 and 9 which extend as far as the bottom 10 of the first slot 2. 75

Into the bosses 5 and 6 are inserted the flanges formed on the cross members 11 and 12. A right-angled end 13 of each flange is imbedded in the lower part 3, whilst the other end 14 forms only an abutment surface in contact with the lower part 3; the holes 15 and 16 are formed in the bosses and serve to secure the piston rod axle. 80

In another embodiment of the invention shown in Fig. 5, the cross members 11 and 12 have their ends disposed in the same manner as the ends 14, forming simple abutment surfaces for the lower part 3 of the piston. 85

In another embodiment shown in Figs. 6 and 7, the cross members 11 and 12 are connected together at their ends by transverse portions and thus form a combined device, and the contact surface is thus increased; furthermore, to better support the lower part 3, there have been provided on the latter the enlarged parts 17 and 18 by which it rests upon the top and bottom of the cross member. 90

Claim:

In a piston for internal combustion engines consisting of a metal having a great coefficient of expansion, cross members of a metal having a small coefficient of expansion, these being fitted at one end into the peripheral part of the piston and a flange adapted for insertion into the hole in the boss of the piston adapted to receive the axle of the piston rod end.

10 In testimony whereof I have hereunto affixed my signature.

CHARLES SCHAEFFER.
